UNITED STATES PATENT OFFICE.

JOHN PHELAN, OF PITTSBURG, PENNSYLVANIA.

GALLEY-LOCK.

SPECIFICATION forming part of Letters Patent No. 442,540, dated December 9, 1890.

Application filed May 19, 1890. Serial No. 352,293. (No model.)

To all whom it may concern:

Be it known that I, JOHN PHELAN, a citizen of the United States, residing at Pittsburg, in the county of Allegheny and State of Pennsylvania, have invented certain new and useful Improvements in Galley-Locks; and I do hereby declare the following to be a full, clear, and exact description of the invention, such as will enable others skilled in the art to which it appertains to make and use the same.

My invention relates to a locking device for printers' galley; and my object is to produce a more simple and effective device, which will greatly facilitate the labor of locking up and unlocking a column of type within a galley, a still further object being to provide a device that will give a uniform pressure upon the type throughout the column, and thereby set them squarely and evenly upon their feet.

With these purposes in view my invention consists in the peculiar features and combinations of parts more fully described herein-after, and pointed out in the claim.

In the accompanying drawings, Figure 1 represents a plan of my device when seen applied to a galley before being locked; Fig. 2, a similar view showing it in locked adjustment, and Fig. 3 an enlarged transverse section through line $x-x$ of Fig. 2.

The reference-letter a represents an ordinary printer's galley containing a column of type a' , to which my lock is applied. This lock consists of two long sections b and c , preferably made of brass or other suitable metal, and these are provided with flat faces d , which are adapted to press against the wall of the galley and side of the type, respectively. A series of lateral webs e , connected by a guide-strip f , extend out at right angles from the face d upon the section b , and these webs are provided with transverse pins g , having the heads h . The opposite section c is provided with a series of webs i , also connected by strips j , and these webs are provided with parallel oblique slots k , forming inclined planes, within which the pins g operate to connect and lock the two sections together.

The slotted section c is provided with a longitudinal extension l , which comes in contact with the end wall of the galley to hold the

section in rigid adjustment while the other section is being pushed forward in the locking operation.

The locking-section b has upon one end a projection m , which extends at right angles to the flat face d and forms a surface to receive the pressure that forces the locking-section forward.

In using my invention the operator places the two sections alongside the column of type within the galley until the longitudinal extension l comes in contact with the end wall of the galley. He then presses against projection m , which slides the section b forward and outward, the flat faces of both sections being at all times kept perfectly parallel to each other by means of the parallel inclined slots.

The advantages of this device are that a whole column of type can be quickly, uniformly, and strongly locked up, thereby setting all the type evenly on their feet and permitting a more perfect proof to be struck off, and accomplishing other desirable results.

It is evident that my invention can be varied in many slight ways which might suggest themselves to a skillful mechanic. Therefore I do not limit myself to the exact construction shown; but,

Having thus described my invention, what I claim as new, and desire to secure by Letters Patent, is—

In a galley-lock, the combination of a pair of movable sections having parallel flat faces adapted to press against the type and side of the galley, respectively, a series of overlapping webs projecting at right angles from said faces, one series of webs being provided with pins having heads and connected by guide-strips, and the other series being provided with parallel oblique slots within which said pins move to spread apart the sections, and a longitudinal extension adapted to come in contact with the end of the galley, as set forth.

In testimony whereof I affix my signature in presence of two witnesses.

JOHN PHELAN.
